CLAIM

The ornamental design for a vanity, as shown and described.

DESCRIPTION

FIG. 1 is a front perspective view of a vanity according to the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Portions of the vanity shown in broken lines are not part of the claimed design.

1 Claim, 4 Drawing Sheets
